Primary Examiner—A. Hugo Word*Assistant Examiner*—Doris Clark*Attorney, Agent, or Firm*—Klarquist, Sparkman, Campbell, Leigh & Winston**[57] CLAIM**

The ornamental design for elongated barrier for a door or a window, as shown and described.

DESCRIPTION

FIG. 1 is a perspective view of the invention in a folded and retracted configuration;

FIG. 2 is a perspective view of the invention in a fully open and extended configuration;

FIG. 3 is an elevational view of the right side of the invention shown in FIG. 1;

FIG. 4 is a bottom view of the invention shown in FIG. 1;

FIG. 5 is a top view of the invention shown in FIG. 1;

FIG. 6 is an elevational view of the left side of the invention shown in FIG. 1;

FIG. 7 is a left end view of the invention shown in FIG. 1; and,

FIG. 8 is a right end view of the invention shown in FIG. 1.
